US00D823066S

(12) **United States Design Patent** (10) **Patent No.:** **US D823,066 S**
(45) **Date of Patent:** ** *Jul. 17, 2018

(54) **COOLER**(71) Applicant: **OTTER PRODUCTS, LLC**, Fort Collins, CO (US)(72) Inventors: **Todd Eichinger**, Fort Collins, CO (US); **Curtis R. Richardson**, Fort Collins, CO (US); **Jonathan B. Rayeski**, Fort Collins, CO (US); **Alan V. Morine**, Fort Collins, CO (US)(73) Assignee: **Otter Products, LLC**, Fort Collins, CO (US)

(*) Notice: This patent is subject to a terminal disclaimer.

(**) Term: **15 Years**(21) Appl. No.: **29/597,956**(22) Filed: **Mar. 21, 2017**(51) LOC (11) Cl. **07-01**

(52) U.S. Cl.

Primary Examiner — Jennifer Rivard*Assistant Examiner* — April Rivas(57) **CLAIM**

The ornamental design for a cooler, as shown and described.

DESCRIPTION

FIG. 1 is a front isometric view of a cooler showing our new design;

FIG. 2 is a rear isometric view thereof;

FIG. 3 is a front view thereof shown on an enlarged scale;

FIG. 4 is a rear view thereof shown on an enlarged scale;

FIG. 5 is a left view thereof shown on an enlarged scale;

FIG. 6 is a right view thereof shown on an enlarged scale;

FIG. 7 is a top view thereof shown on an enlarged scale; and,

FIG. 8 is a bottom view thereof shown on an enlarged scale.

The broken line "otter box" text which forms part of the disclosure is a registered trademark owned by Otter Products, LLC of Fort Collins, Colorado.
